UNITED STATES PATENT OFFICE.

EDGAR P. ELZEY, OF PARKERSBURG, WEST VIRGINIA.

FOLDING CHAIR.

Application filed November 21, 1919. Serial No. 838,763.

To all whom it may concern:

Be it known that I, EDGAR P. ELZEY, a citizen of the United States of America, and resident of Parkersburg, Wood County, 5 State of West Virginia, have invented certain new and useful Improvements in Folding Chairs and the like, of which the following is a specification.

This invention relates to certain improvements in folding chairs and the like, and the object and nature of the invention will be readily understood by those skilled in the art in the light of the following explanation of the accompanying drawings illustrating 15 what I now believe to be the preferred embodiment from among other constructions within the spirit and scope of my invention.

An object of the invention is to provide 20 an improved settee or chair which may be readily folded into a small space for storage or transportation; and which when it is desired to use the same, may be quickly returned to unfolded position, the various 25 parts of the device automatically assuming their correct relation one part to another, thus allowing an inexperienced person to use the chair without inconvenience.

A further object of the invention is to 30 provide a chair of strong and rigid construction, the various parts forming bracing means one for another, and one in which when the device is folded, the various parts 35 are adequately protected against damage during subsequent transportation and storage.

The invention consists in certain novel 40 features in construction and in combinations and arrangements as more fully and particularly set forth and pointed out herein-after.

Referring to the accompanying drawings:

Fig. 1, is a perspective view of a settee when set up.

Fig. 2, is a similar view of the settee when folded.

Fig. 3, is a vertical sectional view showing a settee in set up position, and showing in dotted lines various positions of the seat 50 as it is swung to its folded position.

Fig. 4, is a similar view showing the settee in folded position.

Fig. 5, is a perspective view of a modified form of the invention in set up position.

In the particular embodiment illustrated 55 in Figs. 1, 2, 3 and 4, the invention is shown as a settee or bench arranged to accommodate several persons. It will be obvious however, that the invention is equally as applicable to a chair for a single occupant such 60 as illustrated in Fig. 5, for example, and which will be hereinafter more fully described.

The settee illustrated in Figs. 1, 2, 3 and 4, comprises crossed legs 1 and 2 at each end 65 of the settee, a pivotal connection being provided where the legs cross, as by a bolt 3 preferably retained in position by a riveted head.

When the settee is in its set up position, 70 the legs at each end of the same assume a substantially X shaped formation, the legs 1 which are shown as the outside legs, forming the front support for the settee and being preferably connected adjacent their 75 lower ends by a brace rail 4, and the legs 2 which form the rear support being connected by a similar bracing rail 5 adjacent their lower ends.

The rear legs 2 of the device preferably 80 are of such length as to terminate at their upper front ends at the desired height for a seat; while the rear upper ends of legs 1 are extended upwardly above the plane of the seat to be connected at their ends to the 85 back of the settee.

For this purpose, the back is shown as comprising side rails 6 rising to a suitable height, and connected by a top rail 7, and suitable slats 8 forming the back rest. The 90 ends of legs 1 are connected to the respective side rails 6, as by riveted pivotal bolts 9, the legs engaging the outer faces of the side rails so that the legs 1 are the outermost part of the entire construction at each 95 end of the device, thus forming protection for the ends of the settee during handling of the same.

The lower ends of the side rails of the back extend downwardly so as to abut at their 100 lower ends against the rear legs of the settee and against the brace rail 5 which connects the same, thereby forming a support for the back and providing a strong and rigid construction between the crossed legs 1 and 2, 105 and the back of the settee when it is in its set up position. The lower ends of the side rails are preferably rounded off as shown

at 6', to snugly fit into the angle formed between the brace rail and the rear legs of the device.

The seat of the settee is pivoted between the upper ends of legs 2 at its front end, and loosely rests upon a stretcher rail carried between the side rails 6, at its rear end. Exemplifying this construction, the seat is shown as comprising side carrier rails 10 and an intermediate carrier rail 11, connected by a front carrier rail 12, the side carrier rails being pivotally connected to the respective legs 2 as by riveted pivotal bolts 13. The rear ends of the side and intermediate carrier rails rest upon a stretcher rail 14 secured to the side rail 6 of the back. The seat proper is formed of suitable slats 15 supported by the front, side, and intermediate carrier rails.

In order to maintain the back of the settee in proper relation to the legs thereof, when the settee is folded, a link connection is preferably provided between the side rails of the back and the rear legs of the settee.

For this purpose iron straps 16 are provided, each having a suitable pivotal connection 17 at one end with one of the side rails of the back at their lower ends and a similar connection 17' at its opposite end with the adjacent leg 2.

The straps are of such length and so positioned as to hold the side rails of the back in relative close proximity to the legs 2 as the settee is folded (see Fig. 4), and to accurately guide the end of said side rails into abutting engagement against brace rail 5 and the rear legs 2 when the settee is unfolded (see Fig. 3).

The settee being in set up position as shown in Fig. 1, and it being desired to fold the same, the seat is first swung up and outwardly and then downwardly upon its pivots to the position shown in Fig. 4, and in order to permit such movement of the seat the slats forming the back rest of the settee are shown as terminating at a cross rail 18 a suitable distance above the seat, so as to permit the seat to swing freely. After the seat has been lowered, the crossed legs of the settee are swung toward one another into close juxtaposition, the back at the same time assuming a position between the outside legs 1 adjacent to and substantially parallel with the legs 2, and the seat assuming a similar position between the legs 2 and in close proximity to the back.

When it is desired to unfold the settee to its set up position, the legs are spread apart as shown in Fig. 1, the back automatically moving into engagement with brace rail 5 and legs 2, and the seat is then swung up and out and then down until its carrier rails rest upon the stretcher rail 14 for supporting the same. A structure is thus pro-

vided which is braced throughout to form a rigid construction; and which may be quickly folded and unfolded, the parts at all times maintaining their correct relative positions.

In the modification of the invention illustrated in Fig. 5, showing the invention applied to a chair, the construction is similar to that as just described, except that the intermediate carrier rail of the seat may be dispensed with, and instead of the stretcher rail 14 for supporting the seat, as employed in the settee construction, a turned rod or spindle 14' is preferably employed. The operation and construction of this embodiment of the invention, is otherwise similar to that previously described.

It is evident that various changes, modifications and variations might be resorted to without departing from the spirit and scope of my invention and hence I do not wish to limit myself to the exact disclosures hereof.

What I claim is:

1. In a folding chair and the like, the combination of pivotally connected crossed leg members arranged to be folded side by side, the upper rear portion of said leg members being extended above said seat, a back including side rails pivotally connected to said leg extensions, the lower ends of said side rails being supported upon the lower rear leg members when in set up position, links pivotally connected at opposite ends with the lower ends of said side rails and to said lower rear leg members respectively, said back having a seat supporting ledge, and a seat at its front pivotally joined to and supported by the front upper ends of said leg members and at its rear removably resting on said ledge, whereby when the chair is folded said seat hangs at its upper end from the upper ends of said leg members.

2. In a folding chair and the like, in combination, pivotally connected crossed leg members, a back pivotally joined to the upper rear portions of said members and intermediate its vertical length having a seat supporting ledge, the lower end of said back removably abutting and resting on the lower rear portions of said leg members, a pivotal link connection between said lower end of said back and said lower rear portions of said leg members, and a seat at its front end pivotally joined to and supported by the front upper ends of the leg members and at its rear end removably resting on and supported by said ledge, said seat swingable upwardly and forwardly from said ledge to hang from its front end in front of the back and approximately between the leg members when the chair is folded.

3. In a folding chair and the like, in combination, pivotally-connected crossed folding

leg members, a fixed cross bar secured on the lower rear portions of the leg members, a back intermediate its vertical length pivotally joined to the upper rear ends of the leg members and at its lower end removably abutting and resting on both said rear portions of the leg members and said cross bar, substantially as set forth, links pivotally joining said rear portions of the leg members and said lower end of the back, and a seat.

4. In a folding chair and the like, in combination, pivotally connected crossed leg members arranged to be folded side by side, the upper rear portion of said leg members being extended, a back including side rails pivotally connected to said leg extensions, a fixed cross bar secured on the lower rear portions of the leg members adapted to stiffen said members against lateral movement, the lower ends of the side rails of said back abutting and resting on both said rear portions of the leg members and said cross bar, links pivotally connected at opposite ends with the lower ends of said side rails and to said lower rear leg members, respectively, said back having a seat supporting ledge, and a seat at its front pivotally joined to and supported by the front upper ends of said leg members and at its rear removably resting on said ledge, said seat swingable upwardly, forwardly and downwardly to hang from its front end approximately between the leg members and protected thereby.

5. In a folding chair and the like, in combination, pivotally connected crossed folding leg members, the upper rear portion of said leg members being extended, a back intermediate its vertical length pivotally joined to the upper rear portions of leg members, said back having a seat supporting ledge, and a seat at its front end pivotally connected to the upper front ends of said members and at its rear end removably resting on said supporting ledge, said seat swingable upwardly, forwardly and downwardly to hang in front of and below said back, approximately between said leg members and protected in folded position by the said extended leg members.

6. In combination, in a folding chair and the like, crossed pivotally-joined folding leg members, a cross bar fixed on the lower rear

portions of the leg members and stiffening the same and forming an abutment, a back pivotally joined to the upper rear portions of the leg members and extended downwardly to seat against said abutment and maintain the chair against collapse from set up position, and guide links pivotally joining the back and leg members to control the movements of the leg members and back and assure the seating of the back against said abutment.

7. In a folding chair and the like, in combination, leg members embodying two sets of folding crossed legs, the rear ends of the outside legs being extended upwardly and rearwardly, a cross bar fixed to and bracing the lower rear portions of the leg members, a back arranged between and pivotally joined to said upwardly extended leg ends, the lower end of the back arranged to seat against said bar, vertically swingable guide links coupling said back to the said leg members, said back provided with a seat-upholding ledge, and a free-end vertically-swingable seat at its front end located between the upper front ends of the inside legs and pivotally joined thereto, the free rear end of said seat arranged between said extended rear leg ends and normally resting on said ledge, said seat being freely and independently swingable vertically.

8. In a folding chair and the like, in combination, crossed pivoted folding leg members, the outside leg members being extended upwardly and rearwardly, a back arranged between and pivoted to said extended leg member ends, the lower rear portions of the inside leg members providing top abutments, the lower ends of the back arranged to seat against said abutments to maintain the chair against collapse from set up position, guide links pivotally joining the inside leg members and said back ends to assure seating of said back ends against said abutments, said back providing a seat supporting ledge, and a seat at its front arranged between and pivoted to the front upper ends of the leg members, the seat being otherwise free to normally rest on said ledge and to swing freely and independently extending upwardly in front of the back or downwardly between the inside leg members, the seat ends being protected by the outside leg members.

EDGAR P. ELZEY.
